UNITED STATES PATENT OFFICE.

CHARLES T. CARNAHAN, OF DENVER, COLORADO.

LUBRICATING DEVICE.

No. 838,880.

Specification of Letters Patent.

Patented Dec. 11, 1906.

Application filed July 31, 1906. Serial No. 328,582.

To all whom it may concern:

Be it known that I, CHARLES T. CARNAHAN, a citizen of the United States, residing at Denver, in the county of Denver and State of Colorado, have invented new and useful Improvements in Lubricating Devices, of which the following is a specification.

This invention relates to automatic lubricating devices particularly adapted for lubricating inclosed reciprocatory elements.

Primarily the invention is designed for use in connection with pneumatically-operated tools and other pneumatically-operated devices, yet the invention is adapted for use for any purposes wherein it is found applicable.

To this end the invention consists in providing the interior of the cylinder of a reciprocating element with means for automatically supplying a lubricant to the interior of the cylinder during the movement of the reciprocating element, thereby causing an automatic lubrication of the said element.

The invention further aims to provide a lubricating device which shall be automatic in its action, efficient in its use, durable, and readily set up with respect to the part or parts which is or are to be lubricated.

With the foregoing and other objects in view, the invention consists in the construction, combination, and arrangement of parts hereinafter more specifically described, and illustrated in the accompanying drawings, wherein is shown the preferred embodiment of the invention; but it is to be understood that changes, variations, and modifications can be resorted to which come within the scope of the claims hereunto appended.

In describing the invention in detail reference is had to the accompanying drawings, in which—

Figure 1 is a sectional view showing the adaptation of the lubricating device in accordance with this invention in connection with one end of a pneumatic hammer. Fig. 2 is a like view showing the arrangement of the lubricating device when the hammer is connected to an automatic feeder therefor. Fig. 3 is a like view showing a modification.

Referring to Fig. 1 of the drawings, 1 denotes a cylinder having one end thereof closed through the medium of a cap 2, the cap being interiorly screw-threaded and engaging with the peripheral threads formed on the cylinder. The cap 2 has a protuberance

3, hollowed out, as at 4, so as to provide a lubricant-reservoir communicating with an outlet-channel 6, formed in the top of the cap. An apertured plug 7 is secured in the outer end of the reservoir, and the wall of the opening 8 through the plug 7 constitutes a valve-seat 9 for the valve 10, which is carried above an apertured disk 13, fixed in the plug 7. The valve 10 is retained against its seat through the medium of a contractile and expansible spring 11, which is mounted upon the disk 13. When pressure is applied to the valve 10 the same is removed from its seat, consequently opening the aperture in the plug 7 and allowing the reservoir to be replenished through the apertured disk 13 with a suitable lubricating material. When pressure is removed from the valve 10, the latter automatically seats itself, owing to the action of the spring 11. Arranged within the cap 2 and projecting into the cylinder when the cap is secured to the end of the cylinder is an annular substantially solid or imperforate piece of fibrous material 12, concavo-convex in cross-section and preferably consisting of a piece of tanned, tawed, or otherwise dressed skin of an animal. Said piece of fibrous material forms a pocket 14 within the cap, and completely filling the said pocket is a body of absorbent material 15, preferably a mass of comminuted sponge. When the cap 2 is secured to the end of the cylinder, the perimeter of the said annular piece of material 12 is clamped between the edge of the cylinder 1 and the inner face of the cap. To regulate the feed of the lubricant from the reservoir to the body of absorbent material, the outlet-channel 6 has mounted therein a pin-valve 16, one end of which is formed with a head 17, and the other end is bent over to engage the bottom wall of the reservoir, as at 18, which prevents the pin-valve from passing entirely through the opening—that is to say, the bent-over portion 18 will prevent the valve from passing out of the channel in one direction and the head 17 will prevent the valve from passing out of the channel in the other direction. The pin-valve is adjusted so that there is very little end motion, as the pressure comes on it and is released when the hammer is started. When the tool is started, the oil passes through the channel 6 into the pocket and saturates the absorbent material therein retained. As the annular piece of fibrous material is substantially solid, there are no

holes in it, except the natural pores of the material. Owing to the compression and expansion of the air in the cylinder, enough lubricant finds its way through the leather to lubricate the piston within the cylinder perfectly, and at the same time the feed is slow, so that it is only necessary to fill the reservoir once in about five hours.

In Fig. 2 a portion of an automatic feeder 10 is indicated by the reference character 19, and the said feeder is connected to the cylinder-cap 20. In this connection it will be stated that the cylinder-cap is at its top interiorly provided with a screw-threaded opening into which engages one end of the feeder, the said end of the feeder being exteriorly screw-threaded and engaging with the interior screw-threads of the cap. The binding-nut 21 is provided to prevent separation of 20 the feeder and the cap. That end of the feeder 19 which engages the cap 20 is formed with a pocket 22, constituting a lubricant-reservoir, the wall of said pocket having a screw-threaded opening in which engages a 25 screw-threaded plug 23 of the same construction and with the same valvular arrangement and disk as that referred to in connection with the plug 7. That end of the pocket in the feeder which adjoins the pocket 30 formed in the cap by the concavo-convex piece of fibrous material is closed through the medium of a disk 24, secured to the wall of the pocket in the feeder, said disk being provided with an outlet-channel 25, in which is 35 arranged a valve similar to the valve 16 in Fig. 1.

In Fig. 3 the feeder is indicated by the reference character 26, and the pocket, which constitutes a lubricating-reservoir, by the 40 reference character 27. The wall of the pocket is provided with an opening 28, closed by a plug 29. The opening 28 constitutes a means for filling the reservoir. Secured in one end of the pocket 27 is a plug 45 28^a, having a recess 29^a, which opens into a conducting-tube 30, the latter extending toward the opposite end of the pocket 27. The plug 28^a is furthermore provided with a channel 31, communicating with a pocket 27 50 through the medium of a port 32, in which is arranged a pin-valve 33 of the same construction as the valve 16. (Shown in Fig. 1.) The arrangement shown in Fig. 3 is used when the feeder is connected to a pneumatic hammer 55 for drilling up holes. In the construction shown in Fig. 2 it has been found that when drilling up holes it was somewhat difficult to get all the oil out of the reservoir, whereas by employing the tube 30 it enables when drilling up holes to get all the oil out of the reservoir, as the tube extends close to the bottom wall 34 of the reservoir. The recess 29^a and the channel 31 communicate with the pocket formed by the annular piece of fibrous material secured in the cap.

From the foregoing construction of lubricating device it is evident that a device of such class is set up which will automatically lubricate the interior of the cylinder during the movement of the reciprocating element 70 within the cylinder, and it is thought the many advantages of such form of lubricating device can be readily understood.

Although the lubricating device is shown in connection with a pneumatic hammer as 75 well as an automatic feeder for pneumatic hammers, yet it is understood that the automatic lubricating device can be used and adapted for any purposes wherein it is found applicable.

Having thus fully described my invention, what I claim as new, and desire to secure by Letters Patent, is—

1. An automatic lubricating device for inclosed reciprocating elements embodying a 85 cup-shaped piece of fibrous material arranged in the line of the path of said element and constituting a pocket, a body of absorbent material in said pocket, and means for establishing communication between the said 90 pocket and a lubricant-supply.

2. An automatic lubricating device for inclosed reciprocating elements embodying a cup-shaped piece of fibrous material arranged in the line of the path of said element and 95 constituting a pocket, a body of absorbent material in said pocket, means for establishing communication between the said pocket and a lubricant-supply, and means for regulating the flow of a lubricant from the lubricating-reservoir to said pocket.

3. In an automatic lubricating device, the combination with a cylinder and a reciprocating element arranged therein, of a cup-shaped member formed of porous material 105 secured in one end of the cylinder and constituting a pocket, a body of absorbent material in said pocket, and a lubricating-reservoir carried by the cylinder and communicating with said pocket.

4. In an automatic lubricating device, the combination with a cylinder and a reciprocating element arranged therein, of a cup-shaped member formed of porous material secured in one end of the cylinder and constituting a pocket, a body of absorbent material in said pocket, a lubricating-reservoir carried by the cylinder and communicating with said pocket, and means for regulating the feed of the lubricant from the reservoir to the pocket.

5. A lubricating device for inclosed reciprocating elements comprising a leather cup arranged in the line of the path of said element and through which the lubricant is drawn during the reciprocation of the said 115 element, said cup constituting a pocket, an absorbent body mounted in said pocket, and a lubricant-supply communicating with the said pocket.

6. A lubricating device for inclosed recip-

rocotary elements comprising a leather cup arranged in the line of the path of said element and through which the lubricant is drawn during the reciprocation of the said element, said cup constituting a pocket, an absorbent body mounted in said pocket, a lubricant-supply communicating with the said pocket, and means for regulating the feed of a lubricant from the lubricant-supply to the said pocket.

7. An automatic lubricating device for reciprocatory elements comprising a cup-shaped member formed of porous material arranged in the line of the path of the element and through which the lubricant is drawn, said member constituting a pocket, an absorbent body mounted in said pocket, and a lubricant-reservoir communicating with said pocket.

8. An automatic lubricating device for reciprocatory elements comprising a cup-shaped member formed of porous material arranged in the line of the path of the element and through which the lubricant is drawn, said member constituting a pocket, an absorbent body mounted in said pocket, a lubricant-reservoir communicating with said pocket, and a valve-closure for said reservoir.

9. An automatic lubricating device for reciprocatory elements comprising a cup-shaped member formed of porous material arranged in the line of the path of the element and through which the lubricant is drawn, said member constituting a pocket, an absorbent body mounted in said pocket, a lubricant-reservoir communicating with said pocket, and means for regulating the feed of the lubricant from the reservoir to the pocket.

10. An automatic lubricating device for reciprocatory elements comprising a cup-shaped member formed of porous material arranged in the line of the path of the element and through which the lubricant is drawn, said member constituting a pocket, an absorbent body mounted in said pocket, a lubricant-reservoir communicating with said pocket, means for regulating the feed of the lubricant from the reservoir to the pocket, and a valve-closure for said reservoir.

11. An automatic lubricating device for reciprocatory elements comprising a leather cup arranged in the line of the path of the element and through which the lubricant is drawn during the reciprocation of the element, said cup constituting a pocket, a body of sponge mounted in said pocket, and a lubricant-reservoir communicating with the pocket.

12. An automatic lubricating device for reciprocatory elements comprising a leather cup arranged in the line of the path of the element and through which the lubricant is drawn during the reciprocation of the element, said cup constituting a pocket, a body of sponge mounted in said pocket, a lubricant-

reservoir communicating with the pocket, and means for regulating the feed of the lubricant from the reservoir to the pocket.

13. An automatic lubricating device for reciprocatory elements comprising a leather cup arranged in the line of the path of the element and through which the lubricant is drawn during the reciprocation of the element, said cup constituting a pocket, a body of sponge mounted in said pocket, a lubricant-reservoir communicating with the pocket, means for regulating the feed of the lubricant from the reservoir to the pocket, and a valve-closure for said reservoir.

14. An automatic lubricating device for reciprocatory elements comprising a cup-shaped member formed of porous material arranged in the line of the path of the element and through which a lubricant is drawn during the reciprocation of the element, said member constituting a pocket, an absorbent body mounted in said pocket, a lubricant-reservoir, a channel establishing communication between the reservoir and the pocket for supplying the lubricant to the pocket, and a pin-valve mounted in said channel for regulating the flow of the lubricant.

15. An automatic lubricating device for reciprocatory elements comprising a cup-shaped member formed of porous material arranged in the line of the path of the element and through which a lubricant is drawn during the reciprocation of the element, said member constituting a pocket, an absorbent body mounted in said pocket, a lubricant-reservoir, a channel establishing communication between the reservoir and the pocket for supplying the lubricant to the pocket, a pin-valve mounted in said channel for regulating the flow of the lubricant, and an automatic closable valve for said reservoir.

16. An automatic lubricating device for inclosed reciprocatory elements comprising a lubricant-reservoir having an outlet and a stationary imperforate body arranged in the line of the path of said element and at the front of and of greater diameter than said outlet and through which the lubricant is caused to permeate by the reciprocation of said element thereby lubricating the latter.

17. An automatic lubricating device for reciprocatory elements comprising the combination with a cylinder and a piston reciprocating therein, of a lubricant-supply opening into the cylinder, and an imperforate body arranged in front of the point of communication between the lubricating-supply and the cylinder and through which the lubricant is caused to permeate by the reciprocation of the piston thereby lubricating the latter.

18. An automatic lubricating device for reciprocatory elements comprising the combination with a cylinder and a piston reciprocating therein, of a lubricating-supply open-

- ing into the cylinder at the head thereof, and an imperforate body arranged against the inner face of the head of the cylinder and in the line of the path of said piston and through 5 piston and through which the lubricant is drawn during the reciprocation of said piston, and means for supplying lubricant to one side of said member. 30
- 5 which the lubricant is caused to permeate by the reciprocation of the piston thereby lubricating the latter. 35
19. In an automatic lubricating device, the combination with a cylinder and a reciprocatory element therein, of a cup-shaped member formed of porous material arranged within and secured at one end of the cylinder and constituting a pocket, and a lubricating-reservoir carried by the cylinder and communicating with said pocket. 40
- 10 20. In an automatic lubricating device the combination with a cylinder and a reciprocatory element therein, of a cup-shaped member formed of porous material arranged within and secured at one end of the cylinder and constituting a pocket, a lubricating-reservoir carried by the cylinder and communicating with said pocket, and means for regulating the feed of the lubricant from the reservoir to 45
- 15 the pocket. 50
21. A lubricating device for pistons comprising an imperforate member of porous material arranged in the line of the path of said

22. A lubricating device for pistons comprising a cup-shaped member of porous material arranged in the line of the path of said piston and through which the lubricant is drawn during the reciprocation of said piston, said member constituting a pocket, and a lubricant-supply communicating with the said pocket. 40

23. A lubricating device for pistons comprising a cup-shaped member of porous material arranged in the line of the path of said piston and through which the lubricant is drawn during the reciprocation of said piston, said member constituting a pocket, a lubricant-supply communicating with said pocket, and means for regulating the supply of lubricant to said pocket. 45

In testimony whereof I have hereunto set 50 my hand in presence of two subscribing witnesses.

CHARLES T. CARNAHAN.
